DESIGN FOR A COFFEE MAKER LOWER
BOWL

Herbert G. Blakeslee, Evanston, Ill., assignor to Cory Corporation, Chicago, Ill., a corporation of Delaware

Application February 17, 1947, Serial No. 136,946

Term of patent 14 years

(Cl. D44—26)

To all whom it may concern:

Be it known that I, Herbert G. Blakeslee, a citizen of the United States, residing at Evanston, in the county of Cook and State of Illinois, have invented a new, original, and ornamental Design for a Coffee Maker Lower Bowl, of which the following is a specification, reference being had to the accompanying drawing, forming part thereof, wherein—

Fig. 1 is a side elevational view of a coffee maker lower bowl, showing my new design;

Fig. 2 is a top plan view; and

Fig. 3 is a fragmentary front elevational view thereof.

I claim:

The ornamental design for a coffee maker lower bowl, as shown.

HERBERT G. BLAKESLEE.
